SHEET CLIPPING AND CLASSIFYING
APPARATUSDale L. Schubert, Tacoma, Wash., assignor to
Plywood Research Foundation, Tacoma, Wash.,
a corporation of Washington

Application June 15, 1948, Serial No. 33,050

6 Claims. (Cl. 164—48)

1

This invention relates to sheet clipping and classifying apparatus, and particularly to improvements in means for selectively controlling the classifying or sorting devices in such apparatus. In its preferred form, the invention relates specifically to apparatus for clipping continuous sheets of wood veneer into individual sheets of varying sizes and sorting such individual sheets according to size, or according to size and grade.

The invention applies to that type of apparatus known in the art as a "Coe clipper," this type of apparatus being fully described in United States Patents 1,753,967, issued April 8, 1930, to Thomas Robinson, and 2,005,824, issued June 25, 1935, to George Haumann. Such devices include a reciprocable knife for cutting the sheet, an endless in-feeding conveyor arranged to carry the continuous sheet to the knife, and an off-bearing conveyor on the delivery side of the knife to receive the individual sheets as they are cut from the continuous web. Arranged beside the in-feeding conveyor and synchronized therewith is an endless control chain provided with a plurality of actuating dogs which may be moved manually from an inactive position to an active position. These actuating dogs are spaced along the control chain at given intervals, such as 2". The knife is provided with suitable power means which may be set into action by an electrical switch, as seen in the Robinson patent mentioned above, or the knife may be actuated in response to a purely mechanical control member, as seen in the Haumann patent mentioned above. In either case, the control member which initiates operation of the knife is positioned in the path of the actuating dogs carried by the control chain in such a manner that only those dogs which have been moved to active position will actuate the control member to cause the knife to cut.

Such clippers have the advantage of permitting selected cuts in multiples of a set unit, as 2", and the exact width of the cut depends upon the manual manipulation of selected dog means by the operator. Primarily the operation of clippers of this nature clips the pieces to the largest size up to a maximum predetermined width, as 52", and the exact width of any particular piece depends entirely upon the conditions of the wood as determined by the operator. These pieces of veneer stock of heterogeneous widths are now manually sorted as, for example, pieces of scrap, pieces of usable heart stock having a width of not over 14", pieces of usable sap stock having a width of not over 14", pieces of usable heart stock hav-

2

ing a width from 16" to 26", pieces of usable sap stock having a width of 16" to 26", pieces of usable heart stock having a width from 28" to 40", pieces of usable sap stock having a width of from 28" to 40", pieces of usable heart stock having a width of from 40" to 52", and pieces of usable sap stock having a width of 40" to 52".

As the pieces being clipped are clipped to units having multiples of a common unit, as 2", the multiplicity of widths involved does not make the sorting easier when the sorting is done manually. Of course the advantage of cutting to the width determined by the stock itself is that all usable stock is preserved for the best use to which it can be put.

Broadly stated, the present invention provides means applicable to the type of sheet clipping apparatus just described and capable of sorting the cut sheets from the clipper according to size, or according to size and grade, such sorting being accomplished automatically in response to manual operation of the actuating dogs. Thus, the same manual operation which determines the position of the cut also controls the sorting or classifying operation.

In this respect, the invention is similar to that described in copending application, Serial Number 770,540, filed August 25, 1947, by Harold R. Evans and Dale L. Schubert, and now Patent 2,497,874, issued February 21, 1950. The overall purpose of the invention there described is similar to that of the present invention, and the advantages of and need for mechanical sorting of the cut pieces is there set out in detail. The apparatus employed in the invention set forth in the aforesaid copending application is not applicable to the Coe clipper, however, since it provides no control means capable of operation by the actuating dogs employed in shot clipper. Accordingly, a specific object of the invention is to provide automatic sorter control means applicable to the Coe clipper, that is, to a clipper of the type exemplified in the aforesaid Patents 1,753,967 and 2,005,824.

The above mentioned general objects of my invention together with others inherent in the same are attained by the devices set forth in the following drawings, throughout which like reference numerals indicate like parts:

Fig. 1 is a fragmentary side elevation of the control chain and clipper control switch of a clipper apparatus of the type disclosed in the aforesaid Patent 1,753,967, in combination with a series of

sorter control switches arranged in accordance with the present invention;

Fig. 2 is a view similar to Fig. 1 but showing the control chain and clipper control means of a clipper apparatus of the type disclosed in the aforesaid Patent 2,005,824, in combination with a series of sorter control switches arranged in accordance with the present invention;

Fig. 3 is a view similar to Fig. 1 but showing the control chain and clipper control means of a prior art clipper which is a modification of that disclosed in the aforesaid Patent 2,005,824, in combination with a series of sorter control switches arranged in accordance with the present invention;

Fig. 4 is a schematic diagram illustrating an electrical circuit in accordance with the invention, said circuit embodying the sorter control switches illustrated in Figs. 1-4;

Fig. 5 is a schematic diagram similar to Fig. 4, illustrating a modification of the invention adapted for sorting in accordance with both size and grade.

Fig. 6 is a longitudinal sectional view of one of the pin selectors employed in connection with Fig. 5 and taken substantially on broken line 6-6 of Fig. 8;

Fig. 7 is a sectional view, with parts in plan and parts broken away of the structure of Fig. 6 and taken at substantially 90° to Fig. 6;

Fig. 8 is an end view of a fragment of a chain, a switch, and wiper employing the pin selectors of Figs. 5, 6 and 7;

Fig. 9 is a diagrammatic side elevation of the outbearing conveyor, transfer or classifying conveyors, and transfer conveyor control means employed in a sheet clipper in accordance with the invention;

Fig. 10 is a plan view of the apparatus shown in Fig. 9; and

Fig. 11 is a side elevational view, with some parts illustrated diagrammatically, showing one embodiment of the invention incorporated in a sheet clipper of the type described in the aforementioned Patent 2,005,824.

Referring first to Figure 1 of the drawings, some of the parts illustrated are parts from Fig. 4 of the patent to Thomas Robinson, 10 is a contact dog which was numbered 7 in said Robinson patent, 11 is a lever which was numbered 8 in Robinson, 12 are pins which were numbered 61 in Robinson, 13 and 14 are positioning bars and were numbered 62 and 63 in Robinson, 15 are rollers which were numbered 64 in Robinson, 16, 17 and 18 are fingers which were numbered 70, 71 and 72 in said patent. 19 is a pivot means for the lever 11 and said pivot means was numbered 80 in said patent. Insulating block 20, spring bar 21, contact members 22 and 23, screw 24, insulating bar 25, conductors 26 and 27, and scale 28 are numbered respectively in said patent 62 to 89 inclusive, and 100.

Briefly considered, when fingers 18 contact the block 20, then electrical connection is established between contact bars 22 and 23 to energize the power means (not shown) of the clipper. The operator moves the fingers 18 to such a position to predetermine a cut of the veneer sheet.

According to the present invention, the fingers or dogs 18, in addition to actuating the clipper control, also preselect the operation of sorter conveyors through suitable time delay means. The time delay means, and the sorter control circuits dominated by the time delay means, may be of the type shown in the aforementioned copending

application, Serial Number 770,540. Such a time delay means includes a grooved drum 76, Fig. 4, rotated in a given speed relation to the out-bearing conveyor. A plurality of switch operating lugs 82 are positioned in the groove 83 of the drum, there being sufficient frictional engagement between the lugs and drum to cause the lugs to be carried with the drum unless they are held stationary by the electromagnetically controlled catches 77. As seen in Fig. 9, a sorter conveyor actuating switch 115 is positioned adjacent each groove of the drum, so that a lug released by action of one of the catches 77 will actuate one of these switches, depending upon which catch 77 acts, and will thus cause operation of one of the sorter conveyors 116-118, Figs. 9-10. The time delay between actuation of the catch 77 and actuation of the sorter conveyor is of course determined by the length of time required for the lug 82 to travel from the catch to the switch.

In Fig. 1 herein there is shown a plurality of switches. Referring to Fig. 4 of the drawings there are indicated somewhat schematically switches 29 to 55 inclusive. Some of these switches or fragments of some of these switches appear on Fig. 1 of the drawings, as switches 29, 30, 33, 40, 41, 42, 45, 46, 52 and 53. The switches 29 to 55 inclusive each has a finger or switch operating lever 57. These switches are mounted on the main frame 58 of the machine and with their fingers in the path of travel of the fingers 18 when said fingers have been moved to active positioin. Thus if a finger 18 has been set to cause contact between the contact bars 22 and 23, such finger 18 will also contact the finger 57 of the switches 29 to 55 inclusive and cause one of said switches to complete a circuit to a selected selector means. This circuit arrangement will be explained in connection with Fig. 4 of the drawings herein.

Thus, in Fig. 1 of the drawings there is indicated a chain which is not only used as indicated by Robinson to control the clipping of veneer but which is employed to actuate the switches 29 to 55 inclusive.

Referring now to Fig. 2 of the drawings, there is shown a fragment of Fig. 5 of the said patent to Haumann and there is added thereto devices embodying the present invention. The switches shown in Fig. 2 may be the same switches as those employed in connection with Fig. 1 and therefore they are given similar numbers. These switches are carried by the main frame 59. This main frame 59 bears the number 10 in the patent to Haumann. Chain 60, fingers 61, and castings 62 bear numbers 62, 65 and 54 respectively in said patent.

In the Haumann patent the fingers 61, as numbered herein, operate through mechanical means to control the operation of clipper mechanism. The fingers 61, like the fingers 18, are spaced apart at a selected unit, as 2". The chain of Fig. 1 or the chain of Fig. 2 travel synchronously with the moving sheet of veneer and the operator manually trips a desired finger to preselect the location of the line of cut. At the same time the said fingers, when they pass the switches 29 to 55 inclusive, preselect the operation of the selector means as will be hereinafter described.

Referring now to Fig. 3 of the drawings, a chain is illustrated which is of the type now presently used on the commercial models of the said Coe Manufacturing Company. A chain 63 has hollow pins 64 and such pins slidingly mount

pins 65. On the main frame 66 of the machine are mounted the various switches 29 to 55 inclusive (only switches 29, 30, 33, 34, 41, 45, 52 and 53 being shown in Fig. 3). These switches 29 to 55 inclusive are stationary and their finger members 57 are positioned in the path of travel of pins 65 which have been urged inwardly. Thus the relative position of the switch mechanism in the switches 29 to 55 inclusive will be changed when a pin 65 passing thereby has been urged inwardly, but the relative position of the switch mechanism of any switch will not be changed by pins which have not been urged inwardly. The chain 63 travels synchronously with the veneer. The fingers and the chain are moving from right to left as appears in said drawings. A stop 67 extends the full length of the chain but only a fragment thereof is shown in Fig. 3 in order to clarify the drawings. The operator urges a desired pin 65 against a stop 67 to predetermine the location of the cut. The pins 65 are at unit distances apart, such as 2". Any pin 65 which has been urged against the stop 67 by an operator will be moved inwardly by fixed cam 68. The fixed cam 68 has two cam surfaces 69 and 70 which are disposed at an angle and thus a pin, such as the first one to the left in Fig. 3 (which has not been pushed inwardly by an operator), has its inner end traveling in one line of travel while the trailing pin thereto has its inner end traveling in a second line of travel. Moving along with the chain 63 are cam bars 71. These cam bars 71 have spaced depressing lugs 72. Spaced depressing lugs 72 on each cam bar 71 cooperate with the knife depressing rollers 73 to actuate a desired knife of the clipper. The knife depressing rollers 73 have raised portions 74 and relatively lower portions 75. When the cam bars are in the position of the first one to the left in Fig. 3 of the drawings, then the knife depressing roller 73 does not depress a knife. However, when the trailing cam bar to the cam bar just mentioned is being moved inwardly by reason of its forward travel and the cam surface 69, then lugs 72 cooperate with the raised portion 74 so that a knife 45 is urged through the veneer as the traveling knife passes under knife depressing roller 73.

Functionally considered, the only substantial difference between the structure in the present Coe Manufacturing Company clipper machine 50 and the device illustrated in the patent to Haumann is that the pin and chain indicated and the cam 68 supplant the chain and lug means employed to move the extension 61 and blades 59 disclosed in Haumann (Figs. 4 and 7).

As the clipping mechanism per se is not involved in the present invention, only fragmentary parts of the clipper machines have been indicated. As will now appear, applicant's invention can be employed in connection with any of the various types of clippers where we have a feed chain running synchronously with the veneer and where dogs, including levers, pawls, pins, and the like, are manually tripped by an operator to pre-select the cut.

Now referring to Fig. 4 of the drawings, I have illustrated a combination of the switches 29 to 55 inclusive in combination with a part of the mechanism disclosed in the said co-pending application wherein the applicant herein is one of the inventors. A fragment of four groove-forming wheels 76 are shown in Fig. 4 of the drawings and such parts are numbered 103 in said co-pending application. Also, there are shown four catches 77 which correspond to catches 107

therein, solenoids 78, 79, 80 and 81 which correspond to solenoids 72, 74, 76 and 78 therein. The lugs 82 correspond to the lugs 106 of said application. The grooves 83, 84, 85 and 86 correspond to the grooves 105, 115, 117 and 119 in said application. From this correlation of parts it will appear that whenever the solenoid 78 is energized it is energized in response to the cutting of a piece of usable stock which has a width from 8" to 14". If solenoid 79 is energized the piece being cut has a width from 16" to 26"; if the solenoid 80 is energized we are cutting a piece of stock having a width from 28" to 40"; and if solenoid 81 is energized we are cutting a piece having a width from 42" to 52". In the diagram of Fig. 4, no selection is being made as to whether we are cutting heart stock or sap stock. This additional feature will be discussed in connection with Figs. 5 to 8 inclusive.

Switch 29 (Fig. 4) is normally open and is closed by reason of a pin 65 being in its inner or active position. The remaining switches 30 to 55 inclusive are two-position switches normally biased to a first position in which all of the switches are in series. The said switches are spring loaded so they resume their normal positions after a pin 65 passes but are moved, while being contacted with a pin, to a second position, as indicated. If the predetermined selection is that stock up to 6" shall go to scrap, then switches 30, 31 and 32 will be either in series as indicated or we will have an open circuit whenever the switch position is changed by a passing pin 65 which is in its inner position. Thus if 8" to 14" stock is to be the first selection, then the movable contact blades of these switches 33 to 36, when the switches are moved inwardly, will connect with a common conductor 87. Similarly, switches 37 to 42 inclusive are connected to the conductor 88; switches 43 to 49 inclusive are connected to the conductor 89; and switches 50 to 55 inclusive are connected to the common conductor 90 to provide for respective selections of 16" to 26", 28" to 40", and 42" to 52".

Commencing with a source of energy (conductor 91) energy will pass through switch 29 whenever switch 29 is moved to its closed position by reason of the position of a passing pin 65. Energy will then pass through switches 29 to 55 inclusive unless there has been a change from the normal position of any switch in the series 30 to 55 inclusive which is caused by a passing inwardly projecting pin 65. In the drawings it has been indicated that switch 41 has been closed by a passing inwardly projecting pin 65. Any of the switches 30 to 55 inclusive might have been closed and thus closing of switch 41 is obviously merely an example. Tracing the circuit when switch 41 is closed, we commence with conductor 91, which is a source of electrical energy. The energy passes through switch 29 as it is closed by a passing inwardly projecting pin 65 and continues in series through the various switches until we reach switch 41. As switch 41 has been moved to its full line position by a passing pin 65, energy then passes along conductor 88 through solenoid 78 energizing the same and to the other source of energy, conductor 92. Closing of solenoid 78 releases a lug 82 so the same can travel with the groove 84. As set forth in the said co-pending application Serial Number 770,540, this will at a suitable time delay later operate suitable means on the out-bearing conveyor to deliver the piece of material in an appropriate bin or where desired. Even if any of the switches 42 to 55 are

closed, the circuit to solenoids 80 or 81 will be broken because switch 41 moved out of its first position into its second position, interrupting the flow of current to switches 42-55 inclusive, but completing the circuit to conductor 88.

As the pins continue to move, the pin which moved the switch 41 from its series position to connection with the conductor 88 trips switch 29. At the same time the pin which closed switch 45 (as indicated in the drawing) will be 8" behind the previously mentioned pin and thus will trip switch 33 at the same time that its preceding pin is tripping switch 29. At this time we will have a circuit commencing with conductor 91 through switches 29 to 33 which are in series, then to conductor 87, as switch 33 has been moved out of series position into contact with the conductor 87, then through solenoid 78, and then to conductor 92—the other source of energy. It thus will appear that the traveling pins will energize a suitable solenoid, such as solenoids 73 to 81 inclusive, and the one which is energized will be determined by the length of each of the consecutive pieces. When manually manipulating the trigger mechanism of the chain in clippers of the nature herein discussed, the operator is determining both the leading edge of one piece and the trailing edge of the preceding piece. Thus as the lug representing the leading edge of a piece operates switch 29, then the lug in trailing spaced relation thereto which represents the trailing edge of the piece will operate a suitable switch so that after a time delay a piece can be sorted automatically in accordance with its width. As we have a time delay afforded by the various grooves 83 to 86 and the lugs 82 therein, the switches 29 to 55 can be placed anywhere along the line of travel of the chain (except of course they must be located before the wiper employed in commercial installations to return the pins to their normal out position) as suitable provision can be made in synchronizing of the time delay mechanism to take care of the positions of the switches. In other words, it is not necessary that the switch 29 operate at the exact time that the material is being clipped.

It is thus seen that switch 29 constitutes a normally open master switch and that, to effect energization of one of the electromagnetic actuators 77, switch 29 must be closed and one of the switches 33-55 inclusive must be in its second position. Thus, simultaneous actuation of spaced pairs of switches in the series acts, through the circuit of Fig. 4, to energize an electromagnetic actuator 77, the particular actuator energized depending upon the spacing of the simultaneously actuated switches. It will be noted that the conductors 91 and 92 comprise a control circuit across which the parallel circuits 87-90 may be selectively connected by actuation of a corresponding one of the secondary switches 33-55 from its first, or normal, position to its second position. As seen in Fig. 4, the second position contacts of a different group of the secondary switches are common to the parallel circuits; thus, simultaneous actuation of master switch 29 and any of the switches 33-36 will energize solenoid 78, simultaneous actuation of switch 29 and any of the switches 37-42 will energize the solenoid 79, and so forth. Thus, solenoid 78 is energized whenever a piece of veneer 8"-14" in width is clipped, and the solenoid 79 is energized whenever a piece of veneer 16"-26" in width is clipped.

Thus, each of the actuators 77 is operated selectively in response to the clipping of a given

size (or a size within a given range) of sheet, and as fully described in the aforementioned copending application Serial Number 770,540, operation of each actuator 77 releases a switch operating lug 82 in a different one of the grooves 83-86. If it is desired that the first sorter conveyor (116, Fig. 9) pick up all pieces of veneer in the range of 8"-14" in width, then the electro-responsive control member 119 for the conveyor 116 is connected to the switch 115 adjacent the groove 83 and in the path of travel of the lugs 82 released by energization of the solenoid 78. Similarly, if the second sorter conveyor (117, Fig. 9) is to pick up all pieces 16"-26" in width, the control member 120 for that conveyor is connected to that one of the switches 115 positioned adjacent the groove 84, so that operation of the control member 120 will be effected in response to energization of the solenoid 79, Fig. 4.

Fig. 11 illustrates the general relation of in-feeding conveyor A, clipper B and out-feeding conveyor C when the invention is applied to a clipper of the type described in the aforementioned Patent 2,005,824. The series of switches 29-55, carried by frame member 59, is supported adjacent the control chain 60, as by suitable frame members 130. The chain 60 extends along beside the in-feeding conveyor A. The switches 29-55 are connected, through the circuit shown in Fig. 4, to the electromagnetic actuators of the time delay means 76, which is driven in timed relation with the out-feeding conveyor C. The transfer conveyors, such as conveyor 116, are associated with the out-feeding conveyor C in the manner shown in Figs. 9 and 10, and are actuated by suitable power means controlled by electrical means responding to the switching action of the time delay means 76, in the manner hereinbefore described.

Regardless of whether the chain mechanism 40 follows the disclosure of Fig. 1, 2 or 3, we have the same switches involved and the same circuits which have been described in Fig. 4. In the interest of brevity the same switch numbers have been used in Figs. 1 to 3 as the description 45 of Fig. 4 is equally applicable to Figs. 1 and 2 except that the mechanical type of dog employed involves the fingers 18 of Fig. 1, the fingers 61 of Fig. 2, and the pins 65 of Fig. 3. Also, it is to be understood that the invention is not limited 50 to such type of dog means as the same are merely illustrative of a chain which is timed with the traveling veneer and which has lever or dog means which can be utilized to operate switches 29 to 55 inclusive.

In Fig. 4 no provision was made to indicate 55 a cut of heart stock or sap stock. If it is desired to make a selection for various widths of heart stock and also various widths of sap stock, that is, to select according to both size and grade, then the embodiment of my invention indicated in Figs. 5 to 8 inclusive may be employed. This form of my invention has been illustrated 60 for use in connection with the pin chain type mechanism illustrated in Fig. 3. Also, the means 65 for carrying the pins is not illustrated and the pin chain is diagrammatically illustrated by a plurality of pins some of which are in their in-position and some of which are in their out-position. The pins are numbered 93 in Figs. 5 to 8 as the construction thereof is slightly different than the previously mentioned pins. Referring to Figs. 6 and 8, a portion of the head 70 94 of each of the pins 93 is removed to provide the flattened surface 95. The hollow pins 96 replace the hollow pins 64 and are rigid with

links of the chain. A slot-like recess 97 is provided in the bore of the pin 93 and angularly spaced from said slot, such as 90°, is a semi-spherical recess 98. In the pin 93 there is provided an opening which slidably receives a spring 99 and a ball 100. The location of the recess 97 is such so that when the ball 100 rests therein one surface of the head 94, as the flattened portion 95, is presented to pass under and not move the finger 101 of the switch 102 (Fig. 8). The recess 98 is located so that when the ball 100 rests therein that a rounded portion of the head 94 travels in a path so that it will contact the trigger member 101 and move the switch blade mechanism of switch 102 to its dotted line position of Fig. 5. Thus the switch 102 will have its blade normally in the full line position of Fig. 5, is movable to its dotted line position of said figure by contact with a traveling pin 93 and particularly a rounded portion of head 94, and is spring mounted so that it can return by its spring to its normal position. Also, the switch 102 is positioned so that it will only be in the path of travel of pins 93 which have been manually urged inwardly.

All of the switches, with the exception of switch 102, are the same in both Figs. 4 and 5 and hence are given similar numbers. There are shown four additional groove-forming wheels 76 in Fig. 5. The eight groove-forming wheels 76 and parts associated therewith permit the selection of four widths of stock of sap stock and four widths of stock of heart stock. Thus all of the selections as set forth in the said co-pending application wherein the applicant is one of the inventors, are illustrated. Correlation between the parts illustrated in Fig. 5 herein to the parts illustrated in Fig. 4 of said co-pending application are: groove 83 herein corresponds to groove 104, groove 103 herein corresponds to groove 105, groove 84 herein corresponds to groove 114, groove 104 herein corresponds to groove 115, groove 85 herein corresponds to groove 116, groove 105 herein corresponds to groove 117, groove 86 herein corresponds to groove 118, groove 106 herein corresponds to groove 119, solenoid 78 herein corresponds to solenoid 69, solenoid 107 herein corresponds to solenoid 72, solenoid 79 herein corresponds to solenoid 73, solenoid 108 herein corresponds to solenoid 74, solenoid 80 herein corresponds to solenoid 75, solenoid 109 herein corresponds to solenoid 76, solenoid 81 herein corresponds to solenoid 77, solenoid 110 herein corresponds to solenoid 78. The groove-forming wheels 76 and the catches 77 are the same in both Figs. 4 and 5 herein.

The operator, in manipulating the pins 93, will either urge the desired one thereof merely inwardly or will also angularly move them depending on whether he is cutting heart or sap stock. The switch 102 is positioned so that the flattened surfaces 95 of the pins 93, when up and in, pass under and do not operate the switch 102, and the rounded portions of head 94, when up and in, move switch 102 from its full line to its dotted line position of Fig. 5. If there is more heart stock than sap stock the recesses 97 should be located so that the angular position of the surface 95 when in and not operating switch 102 will obtain when the ball 100 is sliding in and out and is in recess 97. The recess 97 will insure that all pins will retain one given position and the recess 98 will determine another given position of angular movement of the heads 94. A wiper 112 is disposed in the path of travel

of head portions 94 which are in their inward position. Also this wiper is disposed in said path after switch 102. The wiper causes all heads 94 to retain or assume given position—turning some which are not in the desired angular position and not turning the others already in the desired position.

In Fig. 5 of the drawings the parts which are similar to Fig. 4 are given similar numbers to eliminate unnecessary repetition of description and to incorporate at this point the previous description. Also the conductors 87, 88, 89 and 90 are connected respectively to solenoids 107 to 110. The solenoids 107 to 110 are connected to a conductor 111. Thus a selected solenoid 78 to 81 (these are indicated as being energized when the operator is cutting sap stock) will be energized in accordance with the pins 93 which the operator depresses providing the round surface of the head 94 is in a position to move the blade mechanism of switch 102 from its full line position to its dotted line position of Fig. 5. If the face 95 is up and is passing the switch 102 then the switch 102 will remain in its normal position and the conductor 111 will be energized from the source so as to keep the circuit to a solenoid of the group 107 to 110 inclusive depending upon the spacing between a pin 93 adjacent a switch 29 and the next succeeding depressed pin.

In manipulating the pins 93, the form shown requires that the pin at the leading edge of a piece of stock should be angularly positioned as to whether the piece is heart or sap. Also if a head 94 is to be turned it should be turned counter clockwise as respects the showing of Fig. 8.

If a selection is to be made both for the type of stock (sap or heart) as well as to the width of a piece of stock, then the operator must manipulate some means at the time he preselects the cut which will later be reflected in the operation of the solenoids 78 to 81 inclusive and 107 to 110 inclusive. In the present example I have indicated the use of both ends of the traveling pins, one to operate the switch mechanisms to determine selection as to width of the piece, and the other switch mechanism to be operated by a flattened face on the other end of the pin to determine heart or sap stock selection. Obviously, other mechanical expedients, such as two chains, one for heart stock and one for sap stock, pins that are depressable to two different levels, pins carrying lugs which are slideable into and out of desired paths, can all be employed. Thus, it is to be understood that the particular pins of Figs. 5 to 8 inclusive are merely illustrative of a preferred form of my invention.

From the foregoing description of Fig. 5 of the drawings and with consideration of the parts incorporated from previous figures, it is believed that the operation of the structure of Figs. 5 to 8 will be readily apparent to those skilled in this art.

Obviously, changes may be made in the forms, dimensions, and arrangement of the parts of my invention, without departing from the principle thereof, the above setting forth only preferred forms of embodiment.

I claim:

1. In a sheet clipping and classifying apparatus, the combination of a sheet clipper, an in-feeding conveyor arranged to deliver a continuous sheet to said clipper, an out-bearing conveyor arranged to receive individual sheets

in succession from said clipper, a plurality of successive transfer conveyors each movable between an inoperative position and an operative position relative to said out-bearing conveyor, a plurality of electrically controlled power means each arranged to move one of said transfer conveyors, a movable control member synchronized with said infeeding conveyor, said control member including a plurality of actuating elements spaced therealong and each movable between an active and an inactive position, clipper control means positioned adjacent said movable control member and past which said actuating elements pass in succession as said control member is moved, said clipper control means being so constructed and arranged as to be actuated only by such of said actuating elements as are in active position as they pass thereby, a series of control switches arranged along the line of travel of said movable control member and each having an operating member biased into the path of travel of said actuating elements when the elements are in active position, a plurality of actuating circuits each connected to control one of said transfer conveyor power means and each including an actuating switch, a plurality of time delay means each arranged to operate one of said actuating switches and each responsive to the action of an electro-responsive actuator, and circuit means for selectively energizing said electro-responsive actuators in response to simultaneous actuation of different spaced pairs of said control switches.

2. In a sheet clipping and classifying apparatus, the combination of a sheet clipper, an in-feeding conveyor arranged to deliver a continuous sheet to said clipper, an out-bearing conveyor arranged to receive individual sheets in succession from said clipper, a plurality of successive transfer conveyors each movable between an inoperative position and an operative position relative to said out-bearing conveyor, a plurality of electrically controlled power means each arranged to move one of said transfer conveyors, a movable control member synchronized with said in-feeding conveyor, said control member including a plurality of actuating dogs spaced therealong and each movable between an active and an inactive position, clipper control means positioned adjacent said movable control member and past which said actuating dogs pass in succession as said control member is moved, said clipper control means being so constructed and arranged as to be actuated only by such of said dogs as are in active position as they pass thereby, a control circuit, a series of control switches arranged adjacent the line of travel of said movable control member and each having an operating member biased into the path of travel of said dogs when the dogs are in active position, said series including a primary control switch and a plurality of two-positioned secondary control switches; a plurality of actuating circuits each connected to operate one of said transfer conveyor power means and each including an actuating switch; a plurality of time delay means each arranged to operate one of said actuating switches and each including an electro-responsive actuating device, and a plurality of circuit means each connecting one of said electro-responsive actuating devices in said control circuit to be energized only when said primary control switch and one of a predetermined group of said secondary switches are simultaneously actuated.

3. In a sheet clipping and classifying apparatus, the combination of a sheet clipper; an in-feeding conveyor arranged to deliver a continuous sheet to said clipper; an out-bearing conveyor arranged to receive individual sheets in succession from said clipper; a plurality of successive transfer conveyors each movable between an inoperative position and an operative position relative to said out-bearing conveyor; a plurality of electrically controlled power means each arranged to move one of said transfer conveyors; an endless movable control member extending adjacent said in-feeding conveyor and synchronized therewith, said control member including a plurality of actuating dogs spaced therealong and each movable between an active and an inactive position; clipper control means positioned adjacent said endless movable control member and past which said actuating dogs pass in succession as said control member is moved, said clipper control means being so constructed and arranged as to be actuated only by such of said dogs as are in active position as they pass thereby; a control circuit; a plurality of parallel circuits; a series of control switches arranged adjacent the line of travel of said movable control member, each of said control switches having an operating member biased into the path of travel of said dogs when the dogs are in active position, said series including a normally open primary control switch actuatable by its operating member to closed position and a plurality of two-position secondary control switches each normally biased to a first position but actuatable by its operating member to a second position, said primary control switch being located adjacent the delivery end of said in-feeding conveyor and said secondary control switches being spaced back along said conveyor, said primary control switch being connected in series in said control circuit and each of said secondary control switches being arranged to connect one of said parallel circuits across said control circuit when in said second position and to interrupt such connection when in said first position; a plurality of actuating circuits each connected to operate one of said transfer conveyor power means and each including an actuating switch, and a plurality of time delay means each arranged to operate one of said actuating switches, each of said time delay means including an electro-responsive actuating device connected in one of said parallel circuits.

4. In combination in an apparatus of the type described, an in-feeding conveyor, off-bearing sorter means including a plurality of electrically controlled power means for selectively operating said sorter means, an endless movable control member arranged beside said in-feeding conveyor and synchronized therewith, said control member including a plurality of actuating elements spaced therealong at equal intervals and each movable between an active and an inactive position, a series of control switches arranged along the line of travel of said control member and spaced at intervals equal to the spacing of said actuating elements, each of said switches having an operating member biased into the path of travel of said actuating elements when the elements are in active position, a plurality of actuating circuits each connected to control one of said power means and each including an actuating switch, a plurality of time delay means each arranged to operate one of said actuating switches and each responsive to the action of an electro-responsive actuator, and

circuit means for selectively energizing said electro-responsive actuators in response to simultaneous actuation of different spaced pairs of said control switches.

5. In combination in an apparatus of the type described, an in-feeding conveyor, off-bearing sorter means including a plurality of electrically controlled power means for selectively operating said sorter means, an endless movable control member arranged beside said in-feeding conveyor and synchronized therewith, said control member including a plurality of actuating elements spaced therealong at equal intervals and each movable between an active and an inactive position, a series of control switches including a master switch and a plurality of secondary switches, said switches being arranged along the path of travel of said control member with said master switch adjacent the delivery end thereof and said secondary switches spaced back therealong at intervals equal to the spacing of said actuating elements, each of said switches having an operating member biased into the path of travel of said actuating elements when the elements are in active position, a plurality of actuating circuits each connected to control one of said power means and each including an actuating switch, a plurality of time delay means each arranged to operate one of said actuating switches and each responsive to energization of an electro-responsive actuator, and circuit means for selectively energizing said electro-responsive actuators each in response to simultaneous actuation of said master switch and one of a different predetermined group of said secondary switches.

6. In a sheet clipping and classifying apparatus, the combination of a sheet clipper, an in-feeding conveyor arranged to deliver a continuous sheet to said clipper, an out-bearing conveyor

arranged to receive individual sheets in succession from said clipper, a plurality of successive transfer conveyors each movable between an inoperative position and an operative position relative to said out-bearing conveyor, a plurality of electrically controlled power means each arranged to move one of said transfer conveyors, a movable control member synchronized with said in-feeding conveyor, said control member including a plurality of actuating element spaced therealong and each movable between an active and an inactive position, clipper control means positioned adjacent said control member and past which said actuating elements pass in succession as said control member moves, said clipper control means being arranged to be actuated by only such of said actuating elements as are in active position as they pass thereby, a plurality of actuating circuits each connected to control one of said transfer conveyor power means and each including an actuating switch, a plurality of time delay means each arranged to actuate one of said actuating switches and each responsive to the action of an electro-responsive actuator, and electrical means for selectively actuating said electro-responsive actuators in accordance with the spacing between successive ones of the actuating elements of said movable control member which are in active position.

DALE L. SCHUBERT.
